TUFT PILE FABRIC LOOM

Application filed October 1, 1930. Serial No. 485,613.

This invention relates to tuft pile fabric looms, and more particularly to novel mechanism for presenting successive yarn tube frames to the fabric being woven. 5 In weaving tufted pile fabrics, such for example, as Axminster rugs and carpets, a series of yarn tube frames are commonly employed and each tube frame carries a spool or spools having the tuft forming yarns 10 wound thereon in accordance with a predetermined pattern. These tube frames are carried by transporting chains in a well known manner, and as each tube frame reaches a predetermined position above the 15 fabric being woven, it is engaged by transferring means or carriers and presented to the fabric.

The laying of a row of tuft forming yarns in the shed in position to be secured to the 20 fabric by a weft shot is facilitated to a large degree by shifting the tube frame bodily while adjacent the warp and by tilting the same to different inclinations relative to the warp. This manipulation of the tube frame 25 has been secured heretofore through the employment of link connections and cam operated levers.

An important feature of the present invention resides in guide-ways constructed 30 and arranged to accurately guide the manipulation of the tube frame during the pile presenting operations.

A further feature of the present invention resides in the construction in which the 35 movement of the tube frame bodily along the warp is controlled by one form of fixed guide and the tilting movement of the tube frame adjacent the fabric is controlled by a separate and differently shaped guide, with 40 the result that the movements imparted to the tube frame are accurately determined by the shape of the guides.

Through the employment of the fixed guides of the present invention to impart the 45 desired composite movements to a tube frame, the cam mechanism for actuating the tube frame carriers may be more simple in construction than heretofore, since in the present construction it is merely necessary to 50 provide power actuated means for shifting

the tube frame transferring carriers relative to the fixed guides.

The various features of the present invention and novel combinations of parts will be further understood from the following 55 description when read in connection with the accompanying drawings.

In the drawings:—

Fig. 1 is a side elevation with parts in section of portion of a pile fabric loom embodying the features of the present invention. 60

Fig. 2 is a fragmentary front view of one side of a loom provided with the tube frame transferring mechanism of Fig. 1. 65

Fig. 3 is a face view of the tube frame tilting mechanism; and

Fig. 4 is a perspective view of a lever to be described and its cooperative guide-ways.

Pile fabric looms employing a series of 70 tube frames for presenting tuft pile yarns to the fabric in accordance with a predetermined pattern are well known in the weaving art, so that only the portions of the loom with which the features of the present invention are associated have been illustrated 75 in the drawings.

The loom illustrated may have the usual frame 1 for supporting the various operating parts, and at the front of the loom is 80 provided the breast beam 2 over which the woven pile fabric travels as it is advanced towards the front of the loom, and about the usual spike or take-up roll not shown. Back of the breast beam 2 is provided the 85 lay 3 having the reed 4, and the lay is supported by the swords 5 for movement towards and from the front of the loom in a well known manner.

The side frames 1 of the loom are provided with the upwardly extending columns 90 6 adapted to support the harness frames 7 and the tube frame transferring mechanism to be described. The harness mechanism may be operated in a well known manner to 95 shift the warp strands a.

The tube frames 8 may have the usual or any preferred construction, and each tube frame comprises a main bar to which the row of yarn receiving tubes 9 are secured 100

and each tube frame is adapted to rotatably support one or more yarn supply spools 10. The tube frames are advanced to a position to be transferred to the fabric by the 5 conveyor chains 11, which pass around the sprockets 12 mounted upon the shaft 13 that is rotatably supported by the uprights 6.

As each tube frame is advanced by the chains 11 to a position directly below the 10 shaft, it is engaged by transfer mechanism and lowered to a position adjacent the weaving point and as the tube frame approaches the pile inserting position it is desirable to tilt the same to the different positions in 15 which it is shown in dotted lines in Fig. 1, as this tilting movement facilitates the bending of the pile yarns *b* into position to be secured to the fabric by a shot of weft carried by the needle 14.

20 The tube frames are carried to and from the weaving point in the construction shown by arms 15 disposed at the opposite sides of the loom and each arm 15 is pivotally secured at 16 to a supporting bracket 17 which preferably has the bell-crank construction shown. The brackets 17 are supported for rocking movement by the shaft 18 which in turn is swingingly supported by the links 19 that are suspended from the 25 shaft 20 supported by the uprights 6. Each bell-crank bracket 17 has a downwardly extending arm 21 adapted to support a lever 22 for rocking movement upon the pin 23. Each arm 15 is provided at one end with a 30 box-like carrier 24 adapted to embrace and support an end of a tube frame 8. The arrangement is such that the carriers 24 are moved into and out of engagement with the ends of a tube frame by rocking the arms 15 about their pivots 16, this being accomplished by rocking the levers 22 the upper ends of which operatively engage these 35 arms.

The arrangement just described is such 40 that the arms 15 may be lowered by rocking the brackets 17 about the shaft 18 and these arms may be moved bodily in the direction of their length by rocking the links 19 from the full line to the dotted line position 45 of Fig. 1. The carriers 24 are pivotally secured to the arms 15 at 25 so that a tube frame may be tilted about the pivots 25 while supported by the arms 15 but the tilting movement of the carriers 24 in a downward direction is limited by the cooperating stops 26.

The desired movement of a tube frame 8 adjacent the weaving point is secured in accordance with the present invention by providing at each side of the loom a guiding bracket 27 which may be rigidly secured to the upright 6 in the proper position of adjustment by the bolts 28, and each bracket 27 is formed with a curved guiding slot or 60 guide-way 29. In the construction shown

the horizontally extending arm of each pivoted bracket 17 is provided at its outer end with a roller 30 which is attached thereto by a pin 31. The arrangement is such that as the brackets 17 are rocked to move a tube frame towards or from the fabric the rollers 30 will travel in the slots or guide-ways 29 to shift the tube frame lengthwise the warps.

As above stated it is desirable also to impart a tilting movement to a tube frame 75 while adjacent the weaving point, and this is accomplished in accordance with the present invention by providing at each side of the loom frame a second guide-way comprising, in the construction shown, the guide 80 slot 32 formed by providing the plates 33 with the curved ribs 34, and the plates 33 are secured to the uprights 6 by the bolts 35. The tilting movement of the tube frame carriers 24 is controlled by a lever 36 at 85 each side of the loom and which are pivoted between their ends upon the pins 31. Each lever 36 is provided at its upper end with a roller 37 adapted to travel in the slot or guide-way 32 and the lower end of this lever is connected by the link 38 to a carrier 24. Each link 38 preferably is provided at its outer end with a forked head 39 adjustably secured thereto and the prongs of the head 39 are pivotally secured to a sleeve 40 adapted to receive a pin 41 projecting from the carrier 24. This pivoted construction is desirable to accommodate the rocking movement of the arms 15 about the pivots 16.

It is desirable to tilt the tube frame 8 to 100 a substantial degree as it moves towards the fabric and to a less degree as it is withdrawn therefrom, since this tilting movement helps to bend the pile yarns *b* adjacent the tuft yarn positioning plate 42 as 105 will be apparent from Fig. 1. Each guide-way 32 therefore, is preferably given the construction best shown in Fig. 3 in which the rocking element 43 or switch member is pivotally mounted at 44 in the guide-way 110 32 and is urged to the dotted line position of Fig. 3 by the spring 45. The arrangement is such that when the bell-crank brackets 17 are rocked downwardly the pin 37 of each lever 36 will move downwardly along 115 the inclined path 46 and as the brackets 17 are rocked upwardly the pins 37 will move upwardly along the paths 47 as indicated by the arrows. The adjusting bolt 48 may be provided to facilitate a slight adjustment 120 of the plate 33.

Rocking movement of the brackets 17 in timed relation with the other parts of the loom is secured by providing a cam 49 driven from a going part of the loom and adapted to rock the lever 50 having the roller 51, and the lever 50 is connected to the pivoted bracket 17 by the link 52.

It will be seen from the foregoing that when the bell-crank levers 17 are rocked by 125

the link or links 52 the movement of the tube frame 8 will be controlled with a high degree of accuracy by the configuration of the guiding slots 29 and 32.

What is claimed is:

5. 1. In a tuft pile fabric loom, the combination of shed forming mechanism, a series of yarn tube frames, spaced arms for carrying a tube frame to the weaving point and adapted to support the frame for tilting movement relative to the arms, and mechanism for tilting the tube frame while supported by the arms including a curved guide-way and means cooperating therewith and connected to the tube frame. 70
10. 2. In a tuft pile fabric loom, the combination of shed forming mechanism, a series of yarn tube frames, spaced arms for carrying a tube frame to the weaving point and adapted to support the frame for tilting movement relative to the arms, and mechanism for tilting the tube frames while supported by the arms, including a guide-way having a switch member, and cooperating means connected to the tube frame and movable along the guide-way to tilt said tube frame. 75
15. 3. In a tuft pile fabric loom, the combination of shed forming mechanism, a series of yarn tube frames, spaced arms for carrying a tube frame to the weaving point and adapted to support the frame for tilting movement relative to the arms, and mechanism for tilting the tube frame while supported by the arms, including a fixed guide-way having a movable switch member and means cooperating therewith and connected to the tube frame, and power means for shifting said cooperating means to tilt the tube frame. 80
20. 4. In a tuft pile fabric loom, the combination of shed forming mechanism, a series of yarn tube frames, spaced arms for carrying a tube frame to the weaving point and adapted to support the frame for tilting movement relative to the arms, and mechanism for tilting the tube frame while supported by the arms, including a curved guide-way, means cooperating therewith and adapted to be moved by said arms along the curved guide-way, and an operating connection between said cooperating means and tube frame to tilt the latter as said means is varied in position by the curve of the guide-way. 85
25. 5. In a tuft pile fabric loom, the combination of shed forming mechanism, a series of yarn tube frames, spaced arms for carrying a tube frame to the weaving point and adapted to support the frame for tilting movement relative to the arms, and mechanism for tilting the tube frame while supported by the arms including a curved guide-way and a lever connected to the tube frame and having a part movable along the 90
- guide way to cause the lever to tilt the tube frame as the lever is turned by the curved guideway. 95
6. In a tuft pile fabric loom, the combination of shed forming mechanism, a series of yarn tube frames, spaced arms for carrying a tube frame to the weaving point and adapted to support the frame for tilting movement relative to the arms, and mechanism for imparting one character of tilting movement to the tube frame as it is advanced towards the weaving point and a dissimilar tilting movement to the tube frame as it is removed therefrom, including a fixed guide-way having two differently shaped paths and means connected to the tube frame and adapted to follow said paths. 100
7. In a tuft pile fabric loom, the combination of shed forming mechanism, a series of yarn tube frames, spaced arms for carrying a tube frame to the weaving point and adapted to support the frame for tilting movement relative to the arms, and mechanism for tilting the tube frame while supported by said arms including a fixed guide-way, a rocking lever engaging said guide-way and connected to the tube frame and to one of said arms and adapted to be moved by the arm along the guide-way. 105
8. In a tuft pile fabric loom, the combination of shed forming mechanism, a series of yarn tube frames, spaced arms for carrying a tube frame to the weaving point and supported for rocking and lengthwise movement, a fixed guide-way, and means cooperating therewith and connected to said arms to move the arms in the direction of their length as they are rocked to present a tube frame to the fabric. 110
9. In a tuft pile fabric loom, the combination of shed forming mechanism, a series of yarn tube frames, spaced arms for carrying a tube frame to the weaving point and supported for rocking and lengthwise movement, a guide-way supported adjacent the path of each swinging arm, means adapted to follow said guide-ways and connected to said arms to shift the arm lengthwise as they are moved towards the weaving point, a lever connected to the tube frame for rocking the tube frame, and a second guideway engaged by the lever to rock the tube frame as the latter moves towards the weaving point. 115
10. In a tuft pile fabric loom, the combination of shed forming mechanism, a series of yarn tube frames, spaced arms for carrying a tube frame to the weaving point, a fixed guide-way supported adjacent the path of each arm, means upon each arm and adapted to follow a guide-way to guide the travel of the arm, and means for shifting the arms to present a tube frame to the fabric. 120
11. In a tuft pile fabric loom, the combination of shed forming mechanism, a series of 125

yarn tube frames, spaced arms for carrying a tube frame to the weaving point, a fixed guide-way supported adjacent the path of each arm, means upon each arm adapted to follow a guide-way to guide the travel of the arm, means for shifting the arms to present a tube frame to the fabric, and means for tilting the tube frame relative to said arms including a separate guide-way provided with cooperating means connected to the tube frame.

12. In a tuft pile fabric loom, the combination of shed forming mechanism, a series of yarn tube frames, spaced arms for carrying a tube frame to the weaving point, a curved guide-way supported adjacent the path of each arm, means upon each arm adapted to follow the adjacent guide-way to guide the arm movement, means for tilting the tube frame relative to the supporting arms including an auxiliary guide-way provided with cooperating means connected to the tube frame, and means for shifting said arms to thereby advance the tube frame towards the fabric and tilt the tube frame to different positions.

13. In a tuft pile fabric loom, the combination of shed forming mechanism, a series of yarn tube frames, spaced arms for carrying the tube frames to the weaving point, a lever connected to the tube frame for tilting it as it moves towards and from the weaving point and a two track guide engaged by the lever to tilt the tube frame as it moves towards the weaving point and to again tilt the tube frame to a less degree as it is withdrawn therefrom.

In testimony whereof, I have signed my name to this specification.
